UNITED STATES PATENT OFFICE.

JOHN A. CALDWELL, OF VANCOUVER, BRITISH COLUMBIA, CANADA.

COMPASS ELLIPSOGRAPH.

Application filed October 20, 1921. Serial No. 509,172.

To all whom it may concern:

Be it known that I, JOHN A. CALDWELL, a citizen of the Dominion of Canada, residing at Vancouver, in the Province of 5 British Columbia, Canada, have invented certain new and useful Improvements in Compass Ellipsographs, of which the following is a specification.

This invention relates to an ellipsograph 10 which is an improvement on that on which Patent No. 1,235,108 was granted to me on the 31st July, 1917.

The invention is fully set forth in the following specification, reference being 15 made to the drawings by which it is accompanied, in which—

Figure 1 is an elevation view of the instrument showing the device as applied to trace an ellipse.

Fig. 2 is a top view of the attachment 20 of the axial stem or front leg to the supporting leg.

Fig. 3 is a section through the attachment of the axial stem to the upright leg.

Fig. 4 is part elevation showing a full 25 ellipse traced without the axial leg or the back leg being moved.

Fig. 5 is a face view of the supporting foot.

Fig. 6 is a top view of a sliding sleeve 30 with two arms at right angles firmly attached thereto, and also the top of the pencil carrier with knurled nut.

Fig. 7 is a section of the center point of 35 the axial leg.

Similar numerals refer to similar parts.

In these drawings 2 represents an upright or supporting leg of uniform cross section, which leg is pointed at its lower 40 end 4 and has removably attached a foot 3 which has two offsets at right angles to the face which engage point 4 through which it passes and enables leg 2 to be held firmly in an upright position.

The upper end of supporting leg 2 45 passes through a yoke-sleeve 5 and through it is endwise movable, this yoke-sleeve 5 is provided with a clamp 8 which fits the contour of leg 2. The clamp 8 is tightened 50 against the leg by a knurled headed clamp screw 9 which is threaded through the rear wall of yoke-sleeve 5. To this yoke-sleeve 5 is pivotally connected by a hinge joint 6 a front leg 10 of uniform cross section with leg 2, said leg 10 is provided on the bottom 55 end with a removable point 11. This point

is flattened on face and rear having a V shaped slot in the center forming a double point between which a small pin 18 may be inserted and so retain point 11 in the 60 center.

On leg 10 a sleeve 12 is freely movable, having firmly formed thereon two graduated radius bars 13 and 14 located on the upper and under ends of the sleeve 12 and 65 on opposite sides and of different lengths. On bar 14 is shown a removable sliding pencil holder 15 threaded on the upper end and having a slot formed across the center to fit on the graduated bars or arms and 70 provided with a knurled nut 16 and washer on the threaded end. The under end having a socket to hold a pencil 17 firmly when inserted therein.

At Figure 4 is shown a part elevation in 75 which only the one short radius arm is shown on the bottom end of the sleeve and the pencil holder mounted on the reverse edge of the arm, it can be seen by Figure 80 4 that a perfect ellipse can be drawn without changing the instrument from one end of the major axis to the other. This form of the sleeve with one short arm is for small ellipses only.

To use the instrument if for small ellipses 85 the major and minor axes being known, the pencil is set to half the minor axis by sliding carrier 15 along the graduated radius arm 14 and secure it with the knurled nut 16 a small pin 18 is inserted in the 90 intersection of the major and minor axes and point 11 of leg 10 placed against the pin 18 the instrument being upright the yoke-sleeve 5 being slightly slackened and the leg 10 inclined until the pencil point 95 17 is at the adjacent end of the major axis the pivot 6 and clamp 8 may be clamped in yoke-sleeve 5 to support leg 10 in that position, point 4 being on the extended major axis with foot 4 at right angles to the 100 major axis.

The tracing pencil 17 mounted on arm 14 105 may be started at one end of the minor axis to the half of which it has been set the sleeve 12 will move up leg 10 as the pencil traces the curve of the ellipse until the end of the major axis is reached and will then move gradually around and down the leg while 110 tracing the other quarter. The leg 2 may then be transferred to a corresponding position on the major axis produced on the opposite side of the ellipse to trace the other half.

Arm 14 is to be used for small ellipses as the pencil holder may be placed against sleeve 12 and scribe very small ellipses without the end of arm 14 coming in contact with the surface to be traced on, therefor the long arm 13 is required for larger ellipses.

The essential points of difference between this invention and that set forth in the patent before referred to is principally in the structural character of the different parts which bring them more central to one another, which tend to more accuracy and also to more simplicity.

Having now particularly described my invention, I hereby declare that what I claim as new and desire to be protected in by Letters Patent, is:

1. A compass ellipsograph, comprising a leg, a sleeve adjustable along said leg, means for clamping said sleeve in adjusted position on said leg, a second leg pivotally connected to said sleeve, a second sleeve pivotally and slidably mounted on said second leg, graduated arms extending radially from and in opposite directions on said second sleeve, a marking device adapted to be slidably mounted on either of said arms, and means for clamping said device to either arm.
2. A compass ellipsograph, comprising in combination a compass leg, pointed at one end a foot removably clamped on said pointed end for supporting the said leg in an upright position, offsets on the outer face of the foot between which the leg point projects, a yoke sleeve through which said leg is movable endwise with means for clamping it in any position of endwise adjustment, a second leg having a removable double pointed end, the said leg being pivotally connected to said yoke sleeve, means on the pivot and yoke sleeve for clamping said legs at any angular adjustment and with respect to each other, a two armed radius sleeve freely movable on pivot leg, a tracing point holder adjustable on either of radius arm and means to secure it thereon in any desired position.
3. A compass ellipsograph, comprising in combination a tubular leg pointed on one

end, means removably attached to the pointed end for supporting said leg perpendicularly, a yoke sleeve through which this leg is movable, means for securing it at any desired position of endwise adjustment, a second tubular leg pivotally connected to said yoke sleeve, means for securing said second leg in any position of angular adjustment, on the first leg a removable point, flattened on front and rear leaving a V shaped notch to receive a central steady pin, on said second leg, a sleeve having a long and short graduated radius arm, a tracing point holder, means for holding said holder in adjusted position on either arm, and a tracing point socketed in the under end of said holder.

4. In a compass ellipsograph comprising in combination a tubular leg pointed on one end a foot removably attached to the pointed end, said foot having two central offsets projecting beyond the plane of the foot between which the pointed end of said leg projects in line with the two ends of the foot to support said leg in an upright position, a yoke sleeve in which said leg is endwise movable, a clamp provided with a knurled headed clamping screw, threaded through the rear of the yoke sleeve to bind said leg in endwise adjustment, a tubular front leg pivotally connected to the said yokesleeve a knurled nut on the end of the pivot pin together with the back clamping screw in said yokesleeve to secure the pivoted leg in the angular adjustment required, a removable point socketed in the free end of the said leg, a radius sleeve freely movable on this leg, said sleeve having a graduated short arm at one end at right angles to the axis and a longer graduated radius arm opposite end and opposite side, a pencil or tracing point holder provided with a slot adjustable on either arm a knurled nut threaded on the upper end of said holder above the arm slot to secure it in the position required, the said holder being provided with a socket on the under end to hold a tracing point firmly in a central position.

JOHN A. CALDWELL.
